UNITED STATES PATENT OFFICE.

ELLEN WHITCOMB, OF BOSTON, MASSACHUSETTS, ASSIGNOR TO THE BRAIN-
ERD & ARMSTRONG COMPANY, OF NEW LONDON, CONNECTICUT.

DESIGN FOR A TEXTILE FABRIC.

SPECIFICATION forming part of Design No. 22,554, dated June 27, 1893.

Application filed May 1, 1893. Serial No. 472,617. Term of patent 7 years.

To all whom it may concern:

Be it known that I, ELLEN WHITCOMB, a citizen of the United States, residing at Boston, in the county of Suffolk and State of Massachusetts, have invented and produced a new and original Design for a Pattern for a Textile Fabric, of which the following is a specification, reference being had to the accompanying drawing, showing the same.

5 The essential feature of my design for a pattern for a textile fabric consists of a novel configuration for such fabric representing an artistic arrangement of several fronds of so called trailing ferns, the stems of said fronds 10 being, in general, connected, or intersected,

by each other near the center of the complete pattern and radiating therefrom in various directions; the leaves of said fronds being naturally disposed, all as shown.

The design is intended to be repeated 20 throughout the length and breadth of a cut or web of fabric and may be produced either by weaving or by printing, as may be preferred.

What I claim is—

The design for a textile fabric substantially as herein shown and described. 25

ELLEN WHITCOMB.
